UNITED STATES PATENT OFFICE.

GUSTAV A. CARLSON, OF CHICAGO, ILLINOIS, ASSIGNOR TO THE BOYE NEEDLE COMPANY, OF CHICAGO, ILLINOIS, A CORPORATION OF ILLINOIS.

HASP.

Application filed June 6, 1921. Serial No. 475,408.

To all whom it may concern:

Be it known that I, GUSTAV A. CARLSON, a citizen of the United States, residing at 4343 Ravenswood Avenue, Chicago, Illi-

nois, in the county of Cook and State of Illinois, have invented a new and useful Improvement in Hasps, of which the following is a specification.

This invention relates particularly to hasps for use in connection with barn doors or the like.

The primary object is to provide a hasp which can be cheaply manufactured, which can be readily applied, and which is very secure. A further object is to provide such a hasp which is reversible, so that "rights" and "lefts" are not needed.

The invention is illustrated in its preferred embodiment in the accompanying drawing, in which Figure 1 represents a broken perspective view of a door and door jamb equipped with the improved hasp; Fig. 2, a horizontal sectional view, showing the door in closed position, the handle of the latch member being shown brokenly; Fig. 3, a section taken as indicated at the line 3 of Fig. 2; and Fig. 4, a section taken as indicated at the line 4 of Fig. 1.

In the construction illustrated A represents a door; A', a door-jamb or post; B, a keeper secured to the jamb A'; and C a latch device secured to the door and co-acting with the member B.

The keeper B comprises a small sheet-metal plate having an attaching portion 1 provided with holes for receiving screws, and provided at one vertical edge with an arrow-head 1^a and at the other vertical edge with a padlock loop 1^b. The members 1^a and 1^b are preferably formed integrally with the plate 1, by stamping the plate to a suitable form and then bending the members 1^a and 1^b so that they are disposed in planes substantially at right angles to the base portion of the plate. The base portion of the plate is shown secured to the jamb A' by means of the screws 2.

The latch device C preferably comprises a mounting plate 3, which is provided with perforations which accommodate the attaching screws 3^a; a latch plate 4, which is connected with the rear end of the plate 3 by means of a rivet 4^a; and a finger piece 5, which is formed separately from, but is rigidly connected with the latch plate 4.

The door is provided near its free vertical edge with a perforation or slot 6, through which the stem portion of the finger piece 5 extends.

The mounting plate 3 may extend slightly past the vertical free edge of the door, as shown, so that the projecting end portion of the mounting plate will strike the outer surface of the jamb A' when the door closes. The mounting plate is provided with a perforation or slot 7 which registers with the slot 6, through which the stem of the finger piece 5 works. The mounting plate is further provided at its end with an out turned lug or stop 8 which projects into a slot 9, with which the latch plate 4 is provided. The slot 9 is of sufficient dimensions to permit the necessary movement of the latch plate 4, and also is adapted to engage the arrow-head 1^a of the keeper. The arrow is provided at its base portion with a notch 10, which is adapted to engage the upper wall of the slot 9 of the latch member. The latch plate 4 has a portion 4^b which projects past the end of the mounting plate 3 and is adapted to overlie the base portion 1 of the keeper B, thus concealing the screws 2. The projection 4 is equipped with an out turned padlock loop 4^c which is disposed adjacent the loop 1^b when the door is closed, so that a padlock may be applied to the loops 1^b and 4^c.

The latch plate 4 covers the ends of the screws 3^a, which serve to secure the mounting plate to the door.

The finger piece 5 comprises a head portion 5^a and a stem 5^b. The finger piece may be stamped from sheet-metal. The head 5^a is provided with a large perforation 5^c, so that the finger may be readily inserted when it is desired to open the door. The stem 5^b extends through a small perforation or slot 11, with which the latch plate 4 is provided. The finger piece is inserted after the device C has been applied to the door, and is driven in with a tight fit, so that the finger piece virtually becomes a part of the latch plate, for operating purposes. The inner end of the stem 5^b serves as a finger, enabling the latch to be lifted from the inner side of the door.

From the description given, it will be understood that all of the parts of the improved device may be formed of sheet-metal by stamping operations. The stop or pro-

jection 8 is short enough so that the latch 4 can be sprung into position after the mounting plate has been secured by screws to the door. After this, the finger piece 5 is driven into the latch plate so tightly that it cannot be forced out without a great deal of effort, and thus the finger piece will serve as a means for lifting the latch and pulling the door open.

10 By forming the finger piece separately and applying it in the manner described, the improved hasp may be compactly packed for shipping purposes. The stop 8 serves to prevent the latch member from dropping below its proper position when the door is opened. In other words, the stop 8 serves to hold the latch member 4 in such a position that it will ride on the inclined surface of the arrow-head when the door is closed, so that the latch member will automatically engage the keeper.

15 The improved construction is simple, can be manufactured very cheaply, and is thoroughly effective for its purpose. The foregoing detailed description has been given for clearness of understanding only, and no unnecessary limitations should be understood therefrom, but the appended claims should be considered as broadly as 20 permissible in view of the prior art.

30 What I regard as new and desire to secure by Letters Patent is:

1. A device of the character set forth comprising a keeper having two vertical edges lying in substantially parallel planes provided at one vertical edge with a padlock loop and at the other vertical edge with a latch-engaging member, and a latch device comprising a mounting plate provided 35 with screw-receiving perforations, and a latch plate pivotally secured to said mounting plate, said latch plate having an extension adapted to overlie the base portion of the keeper, and having a slot adapted 40 to engage the latch-engaging member of the keeper, and having also at its end a padlock loop adapted to register with the loop of 45 said keeper.

2. A device of the character set forth comprising a sheet-metal keeper having a base portion provided with screw-receiving perforations and having at one vertical edge an out turned padlock loop formed integrally with said base portion and having at the 50 other vertical edge an out turned latch-en-

gaging member formed integrally with said base portion, and a latch device comprising a mounting plate provided with screw-receiving perforations, a latch plate having one end riveted to one end of the mounting plate, and having the other end extending beyond the mounting plate and adapted to overlie the base portion of the keeper, said latch plate having a slot adapted to engage the latch-engaging member of the keeper, and having its end portion bent outwardly and forming a padlock loop adapted to register with the padlock loop of the keeper.

3. A device of the character set forth comprising a keeper having an attaching base and having at one vertical edge an out turned padlock loop and at the other vertical edge a latch-engaging member, and a latch device comprising a mounting plate provided with screw-receiving perforations, said mounting plate having at one end an out turned central lug affording a stop, and a latch plate having its rear end pivotally secured to the rear end of the mounting plate, said latch plate having an extension provided with a slot which freely engages said stop and which also engages the latch-engaging member of the keeper, the extension of said latch plate overlying the base portion of the keeper and being equipped with an out turned padlock loop which registers with said first named padlock loop.

4. A latch device comprising a keeper equipped with a padlock loop and a latch-engaging member, and a latch device comprising a mounting plate, a latch plate having its rear end pivotally secured to said mounting plate and having its intermediate portion provided with a slot which registers with a larger slot with which the mounting plate is provided, said latch plate also having a projecting portion extending beyond the mounting plate and adapted to overlie the base portion of the keeper, said extension being provided with a slot adapted to engage the latch-engaging member of the keeper and having an out turned padlock loop adapted to register with said first named padlock loop, and a separately formed finger piece having a stem extending tightly through the first mentioned slot of said latch plate, said stem being extended to provide a finger accessible for operating the latch from the inner side of the door.

GUSTAV A. CARLSON.
